D. H. KING

RADIATOR SHIELD

Filed March 25, 1926

Patented Oct. 19, 1926.

1,603,958

UNITED STATES PATENT OFFICE.

DAVID H. KING, OF SEATTLE, WASHINGTON.

RADIATOR SHIELD.

Application filed March 25, 1926. Serial No. 97,464.

My invention relates to improvements in radiator shields and one of the objects of my invention is to provide a radiator shield that is especially adapted for installation in school houses by fitting snugly against the wall whereby nothing can fall behind the radiator or the shield. Another object is to provide the shield with a top that slants downwardly and outwardly from the wall at such an angle as to make it impossible for the pupils to sit upon same or place any article thereon. A further object is to provide the top with a centrally disposed reinforcing rib for reinforcing same against possible sagging. A still further object is to provide the shield with a deflector member whose back edge portion normally projects slightly to the rear of the wall frame whereby its resilient tendency insures a snug engagement with the wall when the shield is installed thereon.

With the above and other objects in view which will appear as the description proceeds, the invention consists of the novel construction, adaptation, combination and arrangement of parts hereinafter described and claimed. These objects are accomplished by devices illustrated in the accompanying drawings, wherein—

Figure 1 is a view in side elevation of my radiator shield secured to a wall above a fragmentary portion of a radiator;

Fig. 2 is a view in rear elevation of the radiator shield; and

Fig. 3 is a view in central transverse vertical section taken on a line 3—3 of Fig. 2.

Referring to the drawings throughout which like reference numerals designate like parts, the numeral 5 indicates the wall frame made of relatively thick metal and rectangular in shape with the bottom frame piece eliminated. The top of the shield, designated by the numeral 6, is provided with an upstanding flange 7 that is welded or otherwise secured to the underside of the top member of said frame. The end members 8 are integral with said top and are provided with outstanding flanges 9 that are welded to the undersides of the end frame members as clearly shown in the drawings. The bottom portion 10 of said end members are curved inwardly and are

turned inwardly upon themselves to provide smooth and strong edges.

The top 6 slants downwardly from its flange 7 at an angle of substantially 30 degrees and is curved at its outer end portion 11 in semi-circular fashion, and its extreme edge portion is turned upwardly as at 12 to provide a dust roll 13. A dust retaining pad may be placed within said roll as shown in Fig. 3.

A deflector member 14, having its outer edge in abutment with the turned up edge portion 12, is curved at this point to fit within the dust roll 13 and is welded to the inner side of the curved end 11 of the top 6. Said deflector is curved inwardly and downwardly to its lower inner edge portion 15 that is bent back and doubled upon itself.

The deflector 14 is secured to the ends 8 by sheet metal brackets 16 welded thereto at points above the edge portion 15. As shown in Fig. 3 said edge portion 15 normally projects a slight distance to the rear of the wall frame 5 and the free lower portion of the deflector between the brackets 16 and said edge portion has a tendency to press against the wall upon which the shield is installed. Therefore when the shield is secured to a wall by screws 17 passing through the wall frame as shown in Fig. 1 said deflector edge portion will be pressed inwardly whereby the spring tension will insure a close fit against the wall.

In order to reinforce the slanting top 6, a rib 18 of channeled construction is centrally welded to the underside thereof. Several of such ribs may be used if desired and depending on the length of the shield. It will be understood that the entire device, with the exception of the wall frame 5, is ordinarily made of sheet steel, and all parts are welded with no exterior seams.

Thus it will be obvious that I have provided a radiator shield of simple and durable construction particularly adaptable for use in school houses by reason of the fact that no trash can fall behind it, that is difficult for the pupils to sit upon by reason of its slanting top, and whose top is reinforced against sagging.

Having thus described my device, it being understood that such changes may be re-

sorted to as are within the scope and spirit of the invention, what I claim and desire to secure by Letters Patent is:—

A radiator shield comprising a frame adapted to fit snugly against a wall, end members secured to said frame, a top secured to said frame, and a deflector secured to the underside of said top, said deflector

being curved downwardly and inwardly with its lower edge normally projecting exteriorly of said frame and adapted to resiliently engage said wall. 10

In witness whereof, I hereunto subscribe my name this 19th day of March, A. D. 1926.

DAVID H. KING.
